UNITED STATES PATENT OFFICE.

SALISBURY M. DAY, OF ROCHESTER, NEW YORK, ASSIGNOR TO GENERAL RAILWAY SIGNAL COMPANY, OF GATES, NEW YORK, A CORPORATION OF NEW YORK.

UNIVERSAL A. C. RELAY.

Application filed August 30, 1922. Serial No. 585,212.

This invention relates to indicator attachments for relays used for railway signaling purposes.

In railway signaling practice, it is often found desirable to have information as to the position or condition of a distant signal, switch machine, track circuit or the like. This information is quite often necessary or desirable in towers at switching and interlocking points, and for this reason various indicating devices have been provided for this purpose generally known as tower indicators.

The principal objects and purposes of the present invention are to provide an indicator attachment which may be readily applied to relays used for railway signaling purposes, in order to permit the conversion of a relay into a tower indicator, and vice versa, or to use such indicating relay for both purposes; to provide an indicator attachment which may be housed in the usual relay casing ordinarily provided with transparent walls; and to provide a simple, cheap, efficient and unobscured mechanism for operating the indicator by the relay mechanism.

Other objects and purposes of the invention will appear as the description thereof progresses.

In describing the invention in detail, reference will be made to the accompanying drawings, which show several embodiments of the invention applied to one particular line of relays, and in which:

Figure 1 is a front elevation of a relay for railway signaling purposes having such an indicator applied thereto, a portion of the relay being broken away for clearness;

Fig. 2 is a side elevation of the device shown in Fig. 1, the electro-responsive means and a portion of the casing being shown in cross section;

Fig. 3 is a skeleton view of the essential parts of the operating mechanism of the devices shown in Figs. 1 and 2; and

Fig. 4 is a similar view of a modified form of an indicator attachment applied to a two-position relay of similar construction.

In describing the several forms of the indicator attachment applied to a particular type of relay, with which the invention is to be used, this relay will only be briefly described.

Generally speaking, this relay consists of a casing comprising a skeleton frame 1, having

a removable base plate 2 attached to the bottom thereof by screws 3, a top comprising an insulating terminal or contact board 4 provided with binding posts 5, the skeleton frame 2 being provided with glass panels 6 held in place by flanged retainers, and suitable relay mechanism within this casing 7. More specifically, this relay mechanism comprises trunnion supports 8 suspended from the top wall or terminal board 4, each having a trunnion 9 provided therein, clamped in position by a clamping screw 10. These trunnions engage a socket portion in the spools or bearings 11 contained in the upstanding ends of a carrier bar 12. This carrier bar is provided with insulating posts 13 to which are fastened contact arms 14 and 15 provided with spring contact fingers 16 and 17 terminating in contact tips 18, which are adapted to engage stationary contacts 19 adjustably supported by the binding posts 5.

This carrier bar 12 is supported to have a normal or pendent position to which it may be further biased in any suitable manner (no specific means being shown), and is provided with a hanger bracket comprising a U-shaped or forked member 20 (see Figs. 2 and 3), and having an upstanding ridge 22 to facilitate adjustment of this U-shaped member 20 to the carrier bar 12 by the bolts 23. This U-shaped forked member has each of its ends bifurcated, each of these bifurcations containing a roller 24, which is adapted to tilt the carrier bar in either direction from its pendent position. In order to properly balance the carrier bar with its contacts, in addition to the biasing means heretofore mentioned, this carrier bar has been provided with an L-shaped member 25 for balancing the carrier bar, this member being weighted on one side or the other, as the case may require, by washers 26 fastened thereto by a bolt 27.

In the particular relay illustrated in Figs. 1, 2 and 3, this carrier bar 12 is adapted to be tilted in one direction or the other by an electro-responsive device of the induction motor type. This device generally comprises a vertical shaft 30 provided with a jewel bearing 31 at the bottom, and an adjustable jewel bearing 32 at the top. Pivotally supported on this shaft 30 is an armature or inductor comprising a spider 33,

having a downwardly extending skirt 33^a, this skirt being adapted to move in an air gap between a laminated ring 34 of iron and pole pieces 35 provided with coils 36 and 37.

5 In order to provide frictional engagement between the shaft 30 and the inductor, a friction clutch has been provided comprising friction discs 38 and 39 operatively connected to the shaft 30 between which is 10 a friction disc 40 operatively connected to the spider 33, as shown by the extensions 41 engaging the downwardly projecting lugs 42 of spider 33. These friction discs 38, 39 and 40 are held in engagement with each 15 other by the compression coil spring 43 bearing against the washer 44, which is held in place by a cotter pin 45. The coils 36 and 37 are preferably arranged in a manner similar to the coils of different phase windings of an induction motor, and preferably carry currents which are considerably displaced in phase in order to cause a rotating field for purposes well known to those skilled in the art of induction apparatus of 20 this kind.

The shaft 30 (see Fig. 3) is deformed to provide clearance and a support for the roller 50, and includes projections 51 provided with a connecting pin 52 for pivotally supporting said roller eccentrically with respect to the shaft 30. This roller is preferably of a diameter slightly less than the distance between the rollers 24 in order to provide an anti-friction operative connection between the shaft 30 and the carrier bar 12, and at the same time prevent undesirable lost motion. To the L-shaped balancing member 25 is adjustably fastened an indicator operating arm 53 by cap screws 54. The holes through which these cap screws 54 pass are preferably slightly elongated to permit adjustment of the indicator operating arm 53 with respect to the carrier bar 12.

45 The relay skeleton frame 2 is provided with upstanding ears 55 to which is fastened the indicator base member 56 by screws 57, an upstanding back plate 58 being clamped between the ears 55 and the indicator base 56. The face plate 60 of the indicator is bolted to the back plate 58 by bolts 61 passing through spacing sleeves 62. The indicator base 56 preferably comprises a casting having upstanding extensions 64 and 65, the extension 64 being provided with a bearing portion in which is pivotally supported the indicator shaft 66, the other extension being provided with a bearing or journal pin 67 arranged in alignment with 60 the bearing.

To the rear end of the shaft 66 is clamped a re-enforced eccentric, comprising a back member 70 having extensions 71, 72, 73 and 74. The extension 74 is split as shown, and 65 is clamped on the end of the shaft 66 by

a clamping screw 75, the extension 71 being perforated to receive the journal pin 67, and the other extensions 72 and 73 being connected by a pin 76 to form an eccentric. Adjacent the shaft 66 and on the extensions 70 76 and 65 is pivotally supported an angle lever 80 by a spindle 81 rigidly secured to this angle lever. This angle lever is provided with a pin 82 engaging the indicator operating arm 53, and has its other end 75 provided with a slot through which the pin 76 passes. The front end of the indicator shaft 66 is provided with an indicator 83, having suitable indicia thereon, which is adapted to be read through the opening 84 in the face plate 60.

In the particular arrangement shown, the indicia comprises the letters N (indicating normal), D (indicating deenergized or danger), and R (indicating reverse). This indicator 83 is biased to the reverse position by the weight 85, but in the deenergized position of the relay as shown, this indicator is in its midway, deenergized or danger position, as indicated by the letter D. 90 It is thus seen that when the relay is energized to the normal position, the relay operating arm 53 will operate the eccentric pin 76 through the angle lever 80 to turn the indicator to the normal or N position. On the other hand, when the relay is energized to the reverse position, the indicator operating arm 53 will allow the bias of the indicator due to the weight 85 move the indicator to the reverse position. This peculiar arrangement of mechanical transmitting means has been provided to eliminate the possibility of binding or jamming of such parts, this being done by providing engagement of parts due to the bias of the indicator, thereby affording sufficient clearance without bringing in undesirable lost motion.

In Fig. 4 has been shown a different type of indicator operatively connected to a two-position relay instead of a three-position relay, as shown in Fig. 3. This relay in most respects is the same as the one illustrated in Fig. 3, the main difference being that a U-shaped member 90 is provided with only one bifurcated extension, which is provided with a roller 91, a projecting stop member 92 being provided to limit the movement of the roller in one direction. The contact fingers 16¹ and 17¹ of this two-position relay are preferably adjusted so that the contacts 18¹ are in engagement with stationary contacts 19¹ when the relay is in its energized position. Other contacts may, however, be provided which are in engagement when this relay is in the deenergized position, if desired. Since many of the parts of the structure shown in Fig. 4 are the same as those previously described, they will be given the same reference characters. 110 In the arrangement shown in Fig. 4, the 130

direction of movement of the indicator is opposite to that of the carrier bar 12. This has been accomplished by clamping the reinforced eccentric heretofore described to the shaft 66 in a manner to place the eccentric pin 76 on the opposite side of the indicator shaft 66, a U-shaped operating lever 95 having been substituted for the angle lever 80. This U-shaped operating lever 95 is provided with a slot on one up-standing end thereof through which the eccentric pin 76 passes. The other end is provided with an extending pin 97 adapted to be engaged by the indicator operating arm 53, this U-shaped member 95 being similarly supported to that of the angle lever 80 by a pin 98. The front end of the indicator shaft 66 in this instance is provided with an indicator 99 simulating the usual railway signal semaphore arm. This indicator 99 is biased by its own weight into the position shown against the stop pin 100, another stop pin 101 being provided to limit its movement to and not beyond its operated position. The front plate 60 heretofore mentioned is omitted in the semaphore type indicator shown in Fig. 4.

Although several particular physical embodiments of my present invention have been described, and the operating principles thereof explained; nevertheless, I desire to have it understood that the forms selected are merely illustrative, and do not exhaust all possible physical embodiments of the idea of means underlying my invention.

What I claim and desire to secure by Letters Patent of the United States, is:—

1. In a combined relay and indicator, the combination of an electro-responsive device including a member biased to a neutral position and adapted to be actuated in one direction or the other when said electro-responsive device is energized depending on the manner in which it is energized, contacts controlled by said member, an indicator, means for biasing said indicator to one extreme position, which extreme position does not correspond with said neutral position, and means associated with said electro-responsive device engaging said indicator in a manner to positively operate it in one direction only for urging the indicator against its bias to a position corresponding to the position said member is assuming at the time.

2. An indicator attachment for relays comprising, a shaft, an indicator on said shaft, a stationary journal in line with said shaft but spaced a distance therefrom, and means for pivotally supporting said shaft and driving the same comprising a U-shaped member having one of its legs secured to said shaft, and the other pivoted about said journal, said member being provided with a pin disposed eccentrically with

respect to said shaft and journal; whereby the indicator may be moved to various indicating positions by suitable relay mechanism engaging said pin.

3. An indicator for relays for railway signaling purposes comprising, a shaft, an indicator on said shaft adapted to assume any one of three indicating positions, means for biasing said indicator to one extreme position, an eccentrically disposed member on said shaft, and means actuated by a three position relay, biased to neutral position, adapted to bear against said member in one direction only for urging said indicator to the proper indicating position against such bias.

4. A combined relay and indicator for railway signaling purposes comprising, a casing having transparent walls, a three position electro-responsive device in said casing biased to the middle position, contacts operated by said electro-responsive device, an indicating device adjacent one of the transparent walls comprising a shaft, a three position indicator on said shaft, biasing means for biasing the indicator to one extreme position, which extreme position does not correspond with said middle position, and means extending from said electro-responsive device and cooperating with said indicator to actuate the same against said biasing means to a position corresponding to that of said electro-responsive device.

5. An indicator attachment for relays comprising, a base, a journal and a bearing supported on said base, a shaft extending through said bearing in alignment with said journal, an indicator on the shaft, means clamped on said shaft and pivoted about said journal, said means being provided with an eccentrically disposed pin, and means pivotally supported from said base engaging said pin for operating the same about the axis of said shaft.

6. An indicator attachment for relays comprising, a base, a journal and a bearing supported on said base, a shaft extending through said bearing in alignment with said journal, an indicator on the shaft, a member clamped to said shaft and pivoted about said journal, said member having a pair of extending legs, one of which is clamped to said shaft and the other of which is pivoted about said journal, arms extending from said member, a pin connecting said arms, and means pivotally supported on said base operatively engaging said pin for turning said member about the axis of said shaft and journal.

7. In a relay for railway signaling purposes, the combination of a carrier bar having contacts associated therewith and adapted to assume two extreme positions from its biased neutral position, and of indicating means adapted to be operated by

- said carrier bar comprising, an arm connected to said bar in a position to change the neutral bias of the bar, adjustable counter-weighting means for re-establishing 5 the neutral bias of the carrier bar, and indicating means biased very lightly to one extreme position engaging said bar and movable thereby in one direction only, whereby said indicating means may assume 10 any one of three positions corresponding to the three positions assumed by said carrier bar without a direct mechanical connection.
8. In a relay for railway signaling purposes, the combination of a carrier bar 15 having contacts associated therewith and adapted to assume any one of three positions but biased to the neutral position, and of indicating means adapted to be operated by said carrier bar comprising, an arm connected to said bar in a position to disturb its neutral bias, adjustable counter-weighting means for re-establishing the neutral bias of the carrier bar, and means for indicating the position of said carrier bar 20 operated by said arm.
9. An indicator attachment for relays comprising, a base having a bearing supported thereon, a shaft extending through said bearing having an indicator secured 25 thereto, a journal supported by said base in alignment with said shaft; and means adapted to be moved in response to the movement of a movable part of a relay fastened to said shaft and pivotally supported 30 about said journal for moving said indicator

in response to movement of the movable part of said relay.

10. An indicator attachment for relays comprising, a base having a bearing supported thereon, a shaft extending through said bearing having an indicator secured thereto, a journal supported by said base in alignment with said shaft; and means pivoted about said journal and clamped to 40 said shaft and having an eccentrically located pin operated by means adapted to be engaged by movable means projecting from the movable mechanism of a relay.

11. An indicator attachment for relays 50 comprising, a base having a bearing supported thereon, a shaft extending through said bearing having an indicator secured thereto, a journal supported by said base in alignment with said shaft; and means for 55 operating said indicator comprising, a U-shaped member having aligned openings near the two ends thereof one of which is split between the opening and an intermediate point of the member which end is 60 clamped on said shaft by a screw passing through one and engaging the other split portion and the other end of which is pivoted on said journal, and an eccentrically located pin carried by said last mentioned 65 means operated by a member engageable by movable means projecting from the movable mechanism of a relay.

In testimony whereof I hereby affix my signature.

SALISBURY M. DAY.
